CONTROL DEVICE

Filed March 28, 1928

UNITED STATES PATENT OFFICE

OTTO EDELMANN, OF OAK PARK, ILLINOIS, ASSIGNOR TO WESTERN ELECTRIC COMPANY, INCORPORATED, OF NEW YORK, N. Y., A CORPORATION OF NEW YORK

CONTROL DEVICE

Application filed March 28, 1928. Serial No. 265,264.

- This invention relates to control devices, and more particularly to a control device for obtaining various degrees of adjustment between operating elements of a device.
- 5 An object of this invention is to provide a device embodying relatively adjustable elements arranged to be moved with respect to one another to allow very fine or critical adjustment.
- 10 In order to attain this object a plurality of elements, such as for example the plates of a variable electrostatic condenser, are capable of being moved together or separately as determined by the fineness of the adjustment desired. Specifically, all of the elements are arranged to be moved simultaneously due to the movement of a member in one direction or certain of the elements may be moved individually due to its movement in a different 15 direction.
- 20 A clear understanding of the invention may be had by reference to the following description of one embodiment of the invention taken in conjunction with the accompanying drawings, in which
- 25 Fig. 1 is a fragmentary elevational view of a panel upon which is mounted a dual control dial;
- 30 Fig. 2 is a sectional view thereof taken on the line 2—2 of Fig. 1 looking in the direction indicated by the arrows, and
- 35 Fig. 3 is a fragmentary sectional view thereof taken on the line 3—3 of Fig. 2 looking in the direction of the arrows.
- 40 Referring to the drawing in which the same reference characters designate like parts throughout the several views, a supporting panel designated by the numeral 10 has engraved thereon a suitable dial and a condenser housing designated generally by the numeral 12 is mounted on the rear of the panel concentrically with the dial 11. The condenser housing 12 comprises a cylindrical wall 14, and end portion 15 and an end portion 16 which has a tubular threaded portion 17 projecting through the panel 10 and a nut 18 is threaded thereon for the purpose of securing the condenser housing 12 to the panel 10.
- 45 Mounted within the condenser housing 12
- and attached to the side wall thereof by slotted members 20 and 22 are a plurality of series of plates 23—23 and 24—24. A shaft 25 is rotatably mounted in the condenser housing 12 and is positioned therein by a head 26 formed thereon and a nut 29 threaded upon the end thereof opposite the head 26. The shaft 25 has secured thereto a slotted member 27 having a series of plates 28—28 attached thereto which upon rotation of the shaft 25 cooperate with plates 23—23 to form a variable condenser. Encircling the shaft 25 is a sleeve 30 having attached thereto a slotted member 31 to which are attached a series of plates 32—32 which may cooperate with the plates 24—24 to form another variable condenser.
- 55 The sleeve 30 passes through the tubular portion 17 of the front end 16 and has a threaded portion on the outer end thereof to 60 which a lever 34 is rigidly attached by means of a nut 35. The lever 34 has pivoted at its other end a link 36 which is connected to a bolt 38 by means of which a handle 39 is attached to a slidably arm 40. The arm 40 is 65 slidably mounted in a slot 42 (Fig. 3) formed in the head 26 of the shaft 25 and has a pin 44 mounted in the end thereof opposite the handle 39 to keep the arm 40 from being moved out to a point where the pivoted link 70 and lever members 34 and 36 would form a straight line. An indicator 46 is mounted on the end of the arm 40 to cooperate with the dial 11. A disk 48 is secured to the head 26 and lever members 34 and 36 and is provided 75 with a cutout portion 50 and a depending flange 51 having a portion thereof cut away as indicated at 52.
- 80 The condensers described hereinbefore have the usual electrical connections but since these connections are well known to those skilled in the art and do not form a part of the invention, they have been omitted from the drawing for the sake of simplicity.
- 85 It is believed that the operation of the dual control device will be readily understood from the foregoing detailed description and from the following description of its operation. When it is required to move both sets of movable plates simultaneously the handle 39 100

is moved in an arcuate path, thereby causing the plates 28-28 to rotate since they are mounted on the shaft 25 which has positioned in the head 26 thereof the slidable arm 40 upon which the handle 39 is mounted and also causing the plates 32-32 to rotate since they are connected to the handle 39 by means of the bolt 38, link 36, the arm 34 and the sleeve 30 upon which the member 31 having the plates 32-32 secured thereto is mounted. When it is required to move the plates 32-32 independently of the plates 28-28, the handle 39 is moved in a radial direction causing the link 36 to force the arm 34 to move in an arcuate path and since the arm 34 is fixed to the sleeve 30 upon which the slotted member 31 supporting the plates 32-32 is mounted, the sleeve 30 and the parts supported thereby will be caused to rotate around the shaft 25.

20 Although the dual control embodying the invention is herein illustrated and described as applied to variable condensers, it should be understood that the novel features of the invention may be applied to various other 25 variable units such as inductances, resistances, combinations of electrical testing apparatus, etc., and therefore applicant does not desire to be limited except by the scope of the appended claims.

29 What is claimed is:

1. In a variable electric unit, a plurality of series of stationary members and a dual control device comprising a rotatable shaft, members mounted thereon, members mounted 35 on a sleeve rotatable thereabout, an arm slidably mounted in the head of the shaft, and pivoted members interconnecting the slidable arm and the sleeve, the slidable arm being rotatably movable to simultaneously rotate all the movable members and radially movable to independently rotate the sleeve and the members mounted thereon.

2. In a variable electric unit, a rotatable shaft, members fixedly mounted on the shaft, members rotatable about the shaft, means 45 movable in a circular path to simultaneously rotate all the members, and means movable in a radial direction to rotate the members rotatable about the shaft.

3. In a variable electric unit, a dual control device comprising a rotatable shaft, members fixedly mounted thereon, members mounted on a sleeve rotatable thereabout, an arm slidably mounted in the head of the shaft 55 and pivoted members interconnecting the slidable arm and the sleeve, the slidable arm being rotatably movable to simultaneously rotate all the movable members and radially movable to independently rotate the sleeve 60 and the members mounted thereon.

In witness whereof, I hereunto subscribe my name this 14th day of March A. D., 1928.

OTTO EDELMANN.
